UNITED STATES PATENT OFFICE

ALFRED M. LANE, OF ST. LOUIS, MISSOURI, ASSIGNOR TO MONARCH METAL WEATHER-
STRIP CORPORATION, OF ST. LOUIS, MISSOURI, A CORPORATION OF MISSOURI

METAL WEATHER STRIP

Application filed May 4, 1931. Serial No. 534,806.

This invention relates to metal weatherstrips for windows equipped with sliding sashes, and is an improvement on the metal weatherstrip shown in my Patent No. 1,219,009, dated March 13, 1917. The invention has for its principal objects to preserve all of the advantages of the above strip and at the same time to increase its weatherproofing qualities and to obtain other advantages hereinafter appearing. The invention consists in the improved weatherstrip, and in the construction, combinations and arrangements of parts hereinafter described and claimed.

In the accompanying drawing, which forms part of this specification and wherein like symbols refer to like parts wherever they occur,

Fig. 1 is a fragmentary horizontal cross-section through one side of a window provided with a metal weatherstrip embodying my invention,

Fig. 2 is an enlarged horizontal cross-section through the cooperating portions of the sash and frame members of said weatherstrip and the parts of the window located adjacent thereto,

Fig. 3 is a perspective view of the sash member of said weatherstrip; and

Fig. 4 is a similar view of the frame member of said weatherstrip.

Referring to the accompanying drawing, a portion of the casing or jamb member 1 of an ordinary window frame is shown as arranged for vertical sliding sash 2, the respective walls of the vertical slideway for said sash being formed by a parting strip 3 and a stop member or molding 4. The sash is rabbed, as at 5, along the vertical corner thereof located adjacent to the parting strip 3 to accommodate the slidably interlocked portions of sash and frame members A and B, respectively, of a metal weatherstrip.

The present weatherstrip comprises cooperating strips A and B of sheet metal mounted vertically on the sash 2 and jamb 1, respectively, of the window. The sash strip A is relatively rigid and has a longitudinal beaded groove portion 6 of substantially circular shape in cross-section located within

55 gap of the groove opening toward the parting strip 3. One marginal portion of the sash strip extends laterally from one side of the mouth or gap of the beaded groove portion 6 in the form of a flange 7 that is rigidly secured flatwise, as at 8, to the adjacent side face of the sash, and the opposite marginal portion of said strip is doubled back, as at 9, along the outer face of said beaded groove portion to form a stiff, rounded edge along 60 the opposite side of the mouth thereof.

65 The frame strip B is relatively flexible and comprises a wide flange 10, which is located between the opposing faces of the sash and jamb and is rigidly secured along one marginal portion of said jamb, as at 11, preferably under the stop or molding 4. The opposite free marginal portion of the wide flexible flange 10 of the jamb strip is curved or bent laterally, as at 12, toward the sash and is 70 thence rebent or looped to provide an undercut longitudinal bead or hollow rib 13 of substantially circular shape in cross-section adapted to fit within and be slidably engaged by the beaded groove portion 6 of the sash strip A. The walls of the bead 13 of the frame strip B are brought together flatwise, as at 15, to fit the mouth of the beaded groove portion 6 of the sash strip A; and the frame strip is thence bent laterally of the rib 13, as at 75 16, so as to overlap the adjacent portion of the flange 7 of said sash strip and is thence doubled back upon the portion 16 to provide a flange 17. The flange 17 works loosely in a vertical groove 18 provided therefor in the 80 jamb member of the window frame. In practice the marginal portion 19 of the wide flange 10 of the frame strip is bent at an oblique angle, whereby said portion is adapted to press firmly against the face of the jamb when 85 the strip is nailed thereto.

90 The hereinbefore described arrangement provides a full floating, freely slidable, interlocking joint between the sash and frame member of the weatherstrip which permits the sash to move horizontally to and from the frame and to tilt therein without disturbing the joint, such movement being permitted by the flexibility of the frame strip. It is noted 95 as an important advantage of my invention 100

that the flange 9 of the sash strip is doubled back upon the outer face of the beaded groove portion 6 thereof and thus cooperates with the curved portion 12 of the flexible flange 10 of the frame strip some distance from its edge, thereby preventing said edge from cutting the frame strip. It is also noted that the concave surface of the curved portion 12 of the frame strip serves to prevent spreading of the beaded groove portion 6 of the sash strip; and it also serves as a cam or guide for forcing the double back edge 9 of said beaded groove portion into engagement with the narrow neck portion 15 of the bead 13 of the sash strip after the end portion thereof has been snapped over the bead member 13 of the frame strip. It is also noted that the circular cross-sectional shape of the cooperating bead and groove portions of the two strips is well adapted to resist the tendency for said portions to separate.

What I claim is:

1. A weatherstrip for windows equipped with sliding sashes, said weatherstrip comprising two metal strips, one adapted to be fastened to the window frame and the other to the window sash, one of said strips being relatively rigid and having a longitudinal beaded groove portion, and the other strip being relatively flexible and having a longitudinal bead thereon fitting within the beaded groove portion of said rigid strip, said flexible strip having a concave surface extending along one side of the beaded groove portion of said relatively rigid strip and adapted to engage the adjacent marginal portion of said beaded groove portion.

2. A weatherstrip for windows equipped with sliding sashes, said weatherstrip comprising two metal strips, one adapted to be fastened to the window frame and the other to the window sash, one of said strips being relatively rigid and having a longitudinal beaded groove portion of substantially circular shape in cross-section, and the other strip being relatively flexible and having a longitudinal bead thereon of substantially circular shape in cross-section fitting within the beaded groove portion of said rigid strip, said flexible strip having a concave surface extending along one side of the beaded groove portion of said relatively rigid strip and adapted to engage the adjacent marginal portion of said beaded groove portion.

3. A weatherstrip for windows equipped with sliding sashes, said weatherstrip comprising two metal strips adapted to be fastened to the frame and sash, respectively, one of said strips having a longitudinal beaded groove portion formed therein, and the other strip comprising a relatively wide flange having a longitudinal bead thereon near one of its side margins fitting within the beaded groove portion of the groove strip, the bead strip having a concave surface extending along one

side of the beaded groove portion of the groove and adapted to engage the adjacent curved marginal portion of said beaded groove portion.

4. A weatherstrip for windows equipped with sliding sashes, said weatherstrip comprising two metal strips adapted to be fastened to the frame and sash, respectively, one of said strips having a longitudinal beaded groove portion formed therein, and the other strip comprising a relatively wide flange having a longitudinal bead thereon near one of its side margins fitting within the beaded groove portion of the groove strip, the bead strip having a concave surface extending along one side of the beaded groove portion of the groove, and said side of said beaded groove portion of said groove strip having a doubled-back edge portion adapted to be engaged by the concave surface of said bead strip.

5. A weatherstrip for windows equipped with sliding sashes, said weatherstrip comprising two metal strips, one adapted to be fastened to the window frame and the other to the window sash, the sash strip being relatively rigid and having a longitudinal beaded groove portion of substantially circular shape in cross-section, one marginal portion of said sash strip being doubled back upon one side of the beaded groove portion thereof, and the frame strip being relatively flexible and having a longitudinal bead thereon of substantially circular shape in cross-section fitting within the beaded groove portion of said sash strip, said frame strip having a flange extending along one side of the beaded groove portion of said strip and provided with a concave surface adapted to engage the adjacent doubled back margin of said beaded groove portion.

6. A weatherstrip for windows equipped with sliding sashes, said weatherstrip comprising two metal strips, one adapted to be fastened to the window frame and the other to the window sash, one of said strips being relatively rigid and having a longitudinal beaded groove portion, and the other strip being relatively flexible and having a longitudinal bead thereon fitting within the beaded groove portion of said flexible strip, said flexible strip having a portion that extends along one side of the beaded groove portion of said rigid strip and is inclined toward the mouth of said beaded groove portion.

7. A weatherstrip for windows equipped with sliding sashes, said weatherstrip comprising two metal strips, one adapted to be fastened to the window frame and the other to the window sash, one of said strips being relatively rigid and having a longitudinal beaded groove portion of substantially circular shape in cross-section, and the other strip being relatively flexible and having a longitudinal bead thereon of substantially circular shape in cross-section.

- circular shape in cross-section fitting within the beaded groove portion of said flexible strip, said flexible strip having a portion that extends along one side of the beaded groove portion of said rigid strip and is inclined toward the mouth of said beaded groove portion which is provided with a doubled-back marginal flange adapted to engage said inclined portion.
8. A weatherstrip for windows equipped with sliding sashes, said weather strip comprising two metal strips, one adapted to be fastened to the window frame and the other to the window sash, one of said strips being relatively rigid and having a longitudinal beaded groove portion of substantially circular shape in cross section, and the other strip being relatively flexible and having a longitudinal bead thereon of substantially circular shape in cross-section that is connected to the body portion of said strip by a narrow neck portion, said bead fitting within the beaded groove portion of said rigid strip with the neck portion of said bead extending through the mouth of said beaded groove portion, said flexible strip being provided along one side of said beaded groove portion of said rigid strip with a cam surface adapted to force said side of said beaded groove portion toward the narrow neck portion of the bead on the flexible strip.
9. A weatherstrip for windows equipped with sliding sashes, said weatherstrip comprising two metal strips, one adapted to be fastened to the window frame and the other to the window sash, one of said strips having a longitudinal beaded groove portion of substantially circular shape in cross-section, and the other strip having a longitudinal bead thereon of substantially circular cross-section fitting within the longitudinal beaded groove portion of said first mentioned strip, the circular walls of said longitudinal bead being brought together flatwise to fit the mouth of said longitudinal beaded groove portion.
10. A weather strip for windows equipped with sliding sashes, said weatherstrip comprising two metal strips adapted to be fastened to the frame and sash, respectively, one of said strips having a longitudinal beaded groove portion formed therein, and the other strip comprising a relatively wide flange having a longitudinal bead thereon near one of its side margins fitting within the beaded groove portion of said groove strip, one marginal edge of said beaded groove strip being doubled back upon one side of the beaded groove portion thereof.
11. A weatherstrip for windows equipped with sliding sashes, said weatherstrip comprising two metal strips, one adapted to be fastened to the window frame and the other to the window sash, one of said strips being relatively rigid and having a longitudinal beaded groove portion of substantially circular shape in cross-section, and the other strip being relatively flexible and having a flange extending along one side of the longitudinal groove portion of said rigid strip, said flange of said flexible strip being provided with a longitudinal bead of substantially circular shape in cross-section fitting within the beaded groove portion of said rigid strip, the flange opposing side of the longitudinal beaded groove portion of said rigid strip being doubled back upon the curved outer surface thereof.
- Signed at St. Louis, Missouri, this 1st day of May, 1931.

DISCLAIMER

1,875,173.—*Alfred M. Lane*, St. Louis, Mo. METAL WEATHER STRIP. Patent dated August 30, 1932. Disclaimer filed December 20, 1934, by the assignee, *Monarch Metal Weatherstrip Corporation*.

Hereby disclaims the subject matter of claims 9 and 10 of said Letters Patent, to wit:

“9. A weatherstrip for windows equipped with sliding sashes, said weatherstrip comprising two metal strips, one adapted to be fastened to the window frame and the other to the window sash, one of said strips having a longitudinal beaded groove portion of substantially circular shape in cross-section, and the other strip having a longitudinal bead thereon of substantially circular cross-section fitting within the longitudinal beaded groove portion of said first mentioned strip, the circular walls of said longitudinal bead being brought together flatwise to fit the mouth of said longitudinal beaded groove portion.

“10. A weather strip for windows equipped with sliding sashes, said weather-strip comprising two metal strips adapted to be fastened to the frame and sash, respectively, one of said strips having a longitudinal beaded groove portion formed therein, and the other strip comprising a relatively wide flange having a longitudinal bead thereon near one of its side margins fitting within the beaded groove portion of said groove strip, one marginal edge of said beaded groove strip being doubled back upon one side of the beaded groove portion thereof.”
